UNITED STATES PATENT OFFICE.

NETTIE J. CHINN, OF INGLEWOOD, CALIFORNIA.

DESIGN FOR A DOLL.

Application filed December 21, 1922. Serial No. 4,651. Term of patent 3½ years.

To all whom it may concern:

Be it known that I, NETTIE J. CHINN, a citizen of the United States, residing at Inglewood, in the county of Los Angeles and State of California, have invented a new, original, and ornamental Design for a Doll, of which the following is a specification, reference being had to the accompanying drawing, forming part thereof.

I claim:

The ornamental design for a doll, as shown.

NETTIE J. CHINN.
